United States Patent

Des. 240,397
Patented July 6, 1976

240,397

STUD STABILIZER

David M. Robinson, 6710 NW. 8th St.,
Margate, Fla. 33063

Filed Feb. 27, 1975, Ser. No. 553,581

Term of patent 14 years

Int. Cl. D8—05

U.S. Cl. D8—14

FIG. 1 is a rear view of a stud stabilizer shown fragmented for convenience of illustration;

FIG. 2 is a side view of the stud stabilizer shown fragmented for convenience of illustration;

FIG. 3 is a front view of the stud stabilizer shown fragmented for convenience of illustration;

FIG. 4 is a rear view of the stud stabilizer at a reduced scale; and

FIG. 5 is a sectional view of the stud stabilizer taken on line 5—5 of FIG. 2.

I claim:

The ornamental design for a stud stabilizer, as shown and described.
